UNITED STATES PATENT OFFICE.

ROY LEE LE WRIGHT, OF NEW DULUTH, MINNESOTA.

NON-REFILLABLE BOTTLE.

1,087,267.

Specification of Letters Patent.

Patented Feb. 17, 1914.

Application filed May 15, 1913. Serial No. 767,873.

To all whom it may concern:

Be it known that I, ROY LEE LE WRIGHT, a citizen of the United States of America, residing at New Duluth, in the county of St. Louis and State of Minnesota, have invented 5 certain new and useful Improvements in Non-Refillable Bottles, of which the following is a specification, reference being had therein to the accompanying drawing.

10 This invention relates to non-refillable bottles and has for its object the production of a simple and efficient means for preventing the bottle from being refilled by unauthorized persons.

15 Another object of this invention is the production of a stopper which is provided with efficient means for closing the neck portion of the bottle after the same has been filled.

20 With these and other objects in view, this invention consists of certain novel combinations, constructions and arrangements of parts as will be hereinafter fully described and claimed.

25 In the accompanying drawing: Figure 1 is a central vertical section taken through the neck of the bottle showing the stopper in position. Fig. 2 is a section taken on line 2—2 of Fig. 1. Fig. 3 is a perspective view 30 of the stopper. Fig. 4 is a section taken on line 4—4 of Fig. 1. Fig. 5 is a perspective view of the spring member used in connection with the stopper. Fig. 6 is a side elevation of a tool which is adapted to break 35 the neck of the bottle.

Referring to the accompanying drawing by numerals, 1 indicates a bottle which is provided with a neck 2, this neck 2 being provided with a circumferential groove 3 for allowing the neck to be easily broken from the body. The neck 2 is provided with a plurality of oppositely disposed channels 4 and notches 5. The upper portion of this neck 2 is provided with an inner beveled portion 6 for allowing the stopper member to be easily inserted into the neck.

The stopper member comprises a body 7 having an integral head 8, having the circumferential groove 9 into which the upper 50 portion of the neck 2 is adapted to fit. The body 7 is provided upon its side portions with squared ribs 10 which are adapted to be positioned within the channels 4 while the inner portion of the body 7 is provided with 55 an elongated rectangular pocket 11. A coiled spring 12 having diverging arms 13

and laterally bent lips 14, is positioned within the pocket 11. The lips 14 pass through the guiding apertures 15 formed in the body 7, so as to allow the lips 14 to extend for a distance beyond the side portion of the body 7.

When this device is used, the bottle is first filled at which time the cork stopper 16 is positioned within the inner neck 16'. This inner neck 16' extends evenly with the upper portion of the cork 16 and for a distance above the groove 3. By forming this inner neck 16' in this manner it will also be formed at a spaced distance from the inner sides of the neck 2 and inner neck 16'. When the neck 2 is broken away it will break at the groove 3, and since the inner neck 16' extends for considerable distance beyond this groove there will be no danger 70 of particles of glass falling into the inner portion of the bottle. It will also be seen that by forming this inner neck a comparatively long neck will be left after the main neck has been broken away, the neck 16' constituting a means for allowing the free passage of the liquid which is contained within the bottle. The stopper member is then inserted into the neck until the lips 14 ride upon the beveled portion 6 at which time the spring is compressed. The stopper passes 80 upwardly until the lips 14 rest within the notches 5 at which time the stopper is locked in the neck of the bottle. The head 8 rests squarely upon the upper portion of the neck 85 2 and in this manner forms a tight closure for the upper portion of the neck while the squared ribs 10 rest in the channels 4 and constitute an efficient means for preventing the rotation of the stopper within the neck 90 and in this manner prevents the lips 14 from becoming disengaged with the notches 5. If the ribs were not used, by twisting the stopper within the neck, the lips 14 would strike upon the sides of the notches 5 and would 95 compress the spring so as to allow the lips 14 to become disengaged from the pockets whereby the stopper may easily be removed 100 from engagement with the neck.

When it is desired to break the neck, the tool may be used which comprises the handle 17 and hammer 18. This handle 17 carries at its opposite end the curved body 19 having a glass cutting wheel 20. By positioning this portion 19 around the neck of the bottle 110 and allowing the wheel 20 to ride within the groove 3, the tool may be twisted around the

neck several times so as to cut the neck, at which time the hammer portion 18 may be used to tap the neck and break the upper portion thereof from engagement with the lower portion. After this has been accomplished, the inner neck 16' will carry the cork stopper 16 and will form an efficient closure for the bottle, and since the upper portion of the neck has been broken away any unauthorized filling of the bottle could be easily detected, since the upper portion of the bottle would be missing.

Having thus described the invention, what is claimed as new, is:

- 15 A non-refillable bottle comprising a body, a neck carried by said body, said neck provided with a circumferential groove for allowing the neck to be easily broken, said neck provided with oppositely arranged
- 20 channels, and also with notched portions, a stopper comprising a body and an integral head formed upon said body, said body provided with a plurality of squared ribs upon

its side portions, said body also provided with an elongated rectangular pocket and 25 with a plurality of guiding apertures communicating with said rectangular pocket, a spring comprising a pair of diverging arms terminating in laterally bent lips positioned within said pocket, said lips projecting 30 through said apertures and adapted to engage said notched portions of said neck for holding said stopper within said neck, said rib constituting a means for preventing the stopper from rotating within said neck, said 35 head provided with a groove and adapted to fit snugly upon the upper portion of the neck for forming a tight closure for the neck.

In testimony whereof I hereunto affix my 40 signature in presence of two witnesses.

ROY LEE LE WRIGHT.
